UNITED STATES PATENT OFFICE.

JOHN MORRISON HUNTER, OF NEW YORK, N. Y.

IMPROVEMENT IN HEELS FOR BOOTS AND SHOES.

Specification forming part of Letters Patent No. 124,682, dated March 19, 1872.

To all whom it may concern:

Be it known that I, JOHN MORRISON HUNTER, of the city and county of New York and State of New York, have invented certain new and useful Improvements in Reversible Heels for Boots and Shoes.

My improvement contains some of the features shown in my patent dated April 25, 1871.

The following is a description of what I consider the best means of carrying out the present invention.

The accompanying drawing forms a part of this specification. Figure 1 is a cross-section of the full size of heel. Fig. 2 is a view of the face of metal parts on a line with A, Fig. 1. Fig. 3 is a cross-section of the movable part of heel with its attachments, but differing in some respects from the form shown in Fig. 1. Fig. 4 is a view of the face of metal parts on a line with A^a, Fig. 2.

Similar letters of reference indicate corresponding parts in all the figures.

B is the fixed part of heel. C is a metal plate holding the ring d by the flange b, upon which it revolves. e is rim of ring, beveled inside and outside to a thin edge, and extending nearly to the ground surface of the revolving part of heel. This prevents the leather lifts f and g from spreading, and acts instead of nails to take the wear. It may be made of malleable iron, which also may be case-hardened, if preferred. h h' are screws, let through the holes i i' in the leather lift f f', and which serve to attach the plate C to the fixed part of heel B, and to hold down and keep in position the ring d with its attached leather lifts forming the movable part of heel. m m are screws, serving to attach the ring d to the leather lift f. In Fig. 3, there being no external rim, the nails t t hold the lifts together and take the wear. A few nails may be necessary even when

the rim e e is used, as in Fig. 1. Heads of screws h h', in Figs. 1 and 3, are indicated by letters s s'. In Figs. 2 and 4, r r are holes in ring d for passage of screws m m.

The nature of my improvement may perhaps best be understood by reference to my patent dated April 25, 1871. The screws P of said patent are sunk down into the plate N³, and the leather lifts are attached to the ring m, so that they revolve with it; also, in that patent the central part is movable. In this the plate e is designed to be a fixture.

The holes i and the corresponding screws h being out of the center perform a different function from the hole i' and screw h', which is in the center. The screws out of the center not only attach the plate C, but also prevent it from turning. They increase greatly the stability and firmness of the work. It is possible that one hole, i, at a proper distance from the center, might serve by turning successively into the different positions for the insertion of all the screws h; but I prefer the whole number, as shown.

I claim as my invention—

1. The opening or openings i, by which the screws h are let into plate C, and let through the same into the fixed part of the heel B after the lift f has been attached to the ring d.

2. The metal plate C, attached to the part B, as described, in combination with the revolving ring d, provided with a bearing-surface, f g, as set forth.

In testimony whereof I have hereunto set my name in presence of two subscribing witnesses.

JOHN MORRISON HUNTER.
